(57) **CLAIM**

The ornamental design for a tailor's chalk and case, as shown and described.

DESCRIPTION

FIG. 1 is a perspective view of a tailor's chalk and case in a closed position;

FIG. 2 is a front view of the tailor's chalk and case;

FIG. 3 is a back view of the tailor's chalk and case;

FIG. 4 is a right side view of the tailor's chalk and case;

FIG. 5 is a left side view of the tailor's chalk and case;

FIG. 6 is a top view of the tailor's chalk and case;

FIG. 7 is a bottom view of the tailor's chalk and case; and,

FIG. 8 is a perspective view of the tailor's chalk and case in an open position, wherein the front portion has been rotated around the base so that the chalk is supported in an accessible position.

Oblique line shading indicates a transparent cover member of the case. The broken line shown in FIG. 8 depict a portion of the tailor's chalk that forms no part of the claimed design.
